UNITED STATES PATENT OFFICE

166,054

NECKTIE

Leonard Tarmon, Brooklyn, N. Y.

Application October 2, 1951, Serial No. 16,806

Term of patent 3½ years

(CL. D3—16)

To all whom it may concern:

Be it known that I, Leonard Tarmon, a citizen of United States of America, residing at Brooklyn, in the county of Kings and State of New York, have invented a new, original, and ornamental Design for Neckties, of which the following is a specification, reference being had to the accompanying drawing, forming part thereof.

In the drawing

Fig. 1 is a front view of a necktie, showing my new design;

Fig. 2 is an enlarged fragmentary portion thereof showing one of the embroidered elements in detail; and

Fig. 3 is a cross section taken on line 3—3 of Fig. 2.

I claim:

The ornamental design for a necktie, as shown.

LEONARD TARMON.
